PACKAGE HOLDER FOR CANS AND THE LIKE

Fred J. Ullrich, Kalamazoo, Mich., assignor to Sutherland Paper Company, Kalamazoo, Mich.

Application November 10, 1954, Serial No. 467,980

6 Claims. (Cl. 229—40)

This invention relates to a package holder or carton for packaging a plurality of cans or like containers and other articles.

The main objects of this invention are:

First, to provide a collapsible tubular carton or holder adapted for packaging containers having end projections or recesses which enable the very rapid making of the package unit either by hand or by machinery and one which very securely retains the packaged articles.

Second, to provide an open ended tubular carton or holder of the article retaining type in which the tongues are supported in an inwardly diverging relation to the walls by which they are carried so that effective engagement of the tongues with the packaged article is assured and the tongues are, in effect, stiffened to resist stresses tending to disengage the articles therefrom.

Third, to provide a structure having these advantages which is economical in the amount of stock required and may be economically manufactured in the knock-down form by machinery.

Objects relating to details and economies of the invention will appear from the description to follow. The invention is defined and pointed out in the claims.

A preferred embodiment of the invention is illustrated in the accompanying drawing, in which:

Fig. 1 is a fragmentary side elevational view of a package unit including the holder of my invention.

Fig. 2 is a plan view thereof.

Fig. 3 is a fragmentary longitudinal section on a line corresponding to line 3—3 of Fig. 1, a container being indicated by dotted lines.

Fig. 4 is a fragmentary longitudinal section on a line corresponding to line 3—3 of Fig. 1 of a modification.

Fig. 5 is an enlarged fragmentary vertical section on a line corresponding to line 5—5 of Fig. 3.

Fig. 6 is a plan view of the blank from which the holder is formed with certain parts at one edge in extended position and corresponding parts on the opposed edge folded inwardly to show their relation to the walls.

Fig. 7 is an enlarged fragmentary view on a line corresponding to 7—7 of Fig. 6 showing further details of the structure.

Fig. 8 is a perspective view of the collapsed holder.

Fig. 9 is an inside plan view of a slightly modified form of holder in extended position.

Fig. 10 is a plan view of a plurality of blanks illustrating how the blank of Fig. 9 may be cut from a sheet of stock to utilize substantially all of the material thereof.

Fig. 11 is an end elevational view of the holder in connection with a container illustrating one method of applying the holder to the container or articles packaged.

In Figs. 1 and 2 I illustrate the packaging holder of my invention in its relation to a group of three cans designated by the numeral 101 and having chimes or rims 102 which result in recessed ends 103.

While the holder of my invention is adapted for use in packaging a wide variety of articles it is conveniently illustrated in connection with cylindrical cans having the

2

recessed ends. The holder is desirably formed of an integral blank of paperboard as is illustrated in Fig. 6, and comprises opposed pairs of walls 1 and 2 and 3 and 4 with a sealing flap 5 at one end of the blank lapped upon and secured to the other end of the blank to form a tubular holder. Adhesive for the sealing flap is indicated at 6. The walls 1, 2, 3 and 4 and the flap are arranged in alignment in the blank, the walls and flap being hingedly connected by the hinging scores 7.

10 The opposed pair of walls 1 and 2 are provided with inturned flaps 8 and 9 respectively desirably, as in the embodiment illustrated, at each end and the glue flap is provided with end flaps 10. The flaps 8 and 9 are turned inwardly and adhesively secured to the inner sides of the walls 1 and 2, by adhesive indicated at 11 while the flaps 10 of the glue flap are turned inwardly and secured to the inner side of the glue flap 5 by means of the adhesive indicated at 12.

15 The walls 3 and 4 are provided with inwardly directed tongues 13 which are desirably connected thereto by the scores 14. The scores 15 facilitate the folding of the flaps 8 and 9 upon the inner sides of the walls to which they are secured. The tongues 13 are springably supported in diverging relation to the side walls 3 and 4 due to the inherent resiliency of their hinge connections 14 to the side walls, resulting from compression and tension of the stock material on the inner side and outer side, respectively, of their hinge joints, when the tongues are folded inwardly. The tongues are yieldably or springably supported in inwardly diverging relation to the walls from which they extend by the links or struts 16 which are flexibly connected to the ends of the flaps 8, 9 and 10 by flexing scores 17 disposed in alignment with the wall hinging scores 7. The struts are flexibly connected to the tongues by means of flexing scores 18.

20 When the blank is in the flat as shown in Fig. 7, the tongues are collapsed flat upon the inner sides of the walls as shown in Fig. 7. However, when the holder is erected from the collapsed position of Fig. 7 to the erected position of Fig. 5 end thrust is applied to the struts and the tongues are automatically swung to and yieldably supported with their ends spaced relative to and in inwardly diverging relation to the walls by which they are carried so that they are positively engaged with the recesses or projections of the packaged article positioned in retained relation thereto. When the holder is flat or collapsed as shown in Figs. 3 and 7 the distance between the hinged connections 17 of the struts 16 to the flaps 8 and 9 is the same as the distance between the hinge connections 7 of the side walls 1, 2, 3 and 4 to each other, but when the holder is erected as shown in Fig. 5 with the flaps 8, 9 and 10, struts 16, and tongues 13 all disposed on the inner sides of the side walls 1, 2, 3 and 4 then the distance between the hinge connections 17 of the struts is less than that between the hinge connections 7 of the side walls to each other. This results in the endwise thrust on the struts 16, above described, when the holder is erected from a collapsed position to a setup position. The struts serve to reinforce the tongues so that they cannot become crumpled or bent and thereby release the package with which the article is engaged without such force being applied as would destroy the package. They may be released if desired by inserting a knife blade or like implement to lift the tongues.

25 The open packaged articles may be inserted sidewise into the holder from the ends thereof or the holder may be wrapped around the group of articles by positioning the group upon one of the walls provided with the retaining tongues and the walls 1 and 2, and opposed tongue carrying wall swung to erected position, the holder being shown in partially erected position in Fig. 11 to

illustrate certain of the steps for thus assembling the package.

The tongues of the top wall, which should be the wall 3, swing into diverging relation relative to the wall 3 and automatically engage within the upper recesses of the packaged articles as the walls are swung to position to secure the sealing flap to the wall 2 by the adhesive 6. This method of assembling the package is, in effect, wrapping the holder around the group of packaged articles.

The embodiment shown in Figs. 9 and 10 is the same as that described with the exception that in cutting out the blanks they are arranged so as to economize on stock, the tongues of one adjacent blank being cut out of the stock between the pairs of flaps 19.

In the embodiment of Fig. 6 the flaps 8, 9 and 10 correspond in width to the width of the tongues 13. In the embodiment of Fig. 9 the flaps 19 are narrower which permits further saving of stock as shown in Fig. 10; they however, serve as effective anchoring means for the link-like struts 20 which are connected thereto by the flexing scores 21 aligned with the wall hinging scores 7. The struts or links 20 are flexibly connected to the tongues 22 at 23, otherwise the structure is the same as that of the embodiment shown in the blank of Fig. 6.

In the embodiment shown in Fig. 6 portions of the flaps 8, 9 and 10 are cut out at 24 to enable somewhat more flat collapsing. However there are no such cut out portions in the embodiment of Figs. 9 and 10.

I have illustrated and described my invention in a very practical embodiment thereof. I have not however attempted to illustrate or describe various adaptations that might be desirable for the packaging of articles than those illustrated as it is believed that such modification would be apparent to those skilled in the art.

Having thus described the invention, what is claimed as new and desired to be secured by Letters Patent is:

1. A tubular holder for packaging containers having projecting rims at the ends thereof, said holder being formed of an integral cut and scored blank of paperboard or the like and comprising four walls and a sealing flap disposed in alignment in the blank and connected by hinging scores, one opposed pair of walls and the sealing flap having integral end flaps of substantial width folded inwardly upon and fixedly secured to the inner sides thereof in parallel relation thereto, the other pair of opposed walls having inturned container rim engaging tongues disposed approximately parallel thereto and springably connected to the ends thereof, the tongues adjacent their swinging inner ends being connected to the adjacent end flaps by integral links having flexing connections to the tongues and flexing score connections to the flaps aligned with the said hinging scores, whereby when the walls are in erected position the said connecting links are subjected to endwise thrust and the tongues are springably supported with their swinging inner ends in diverging relation to the inner sides of the walls to which they are springably connected thereby facilitating their engagement and retention of their engagement within the rims of packaged containers positioned between the first mentioned pair of walls.

2. A collapsible tubular holder for packaging articles having recessed ends, said holder being formed of an integral blank of paperboard or the like and comprising four hingedly connected walls, one opposed pair of walls having integral end flaps folded inwardly upon and fixedly secured to the inner sides thereof in parallel relation thereto, the other pair of opposed walls having inturned article engaging tongues disposed approximately parallel thereto and swingably connected to the ends thereof, the tongues being connected to the adjacent flaps by integral links having flexing connections to the tongues and having flexing connections to the flaps, the flexing connection to the flaps being aligned with the hinging connections of adjacent pairs of walls, whereby when

the walls are in erected position the straps are subjected to endwise thrust and the tongues are yieldably supported in inwardly diverging relation to the walls to which they are connected.

5 3. A collapsible tubular holder for packaging articles having recessed ends, said holder being formed of an integral blank of paperboard or the like and comprising four hingedly connected walls, one opposed pair of walls having flaps on at least one end thereof folded inwardly upon and fixedly secured to their inner sides in parallel relation thereto, the other pair of opposed walls having inwardly projecting article engaging tongues disposed in side by side relation thereto, and links integrally connecting the tongues to the adjacent flaps and having flexing connections therewith aligned with said hinging connections of the adjacent pairs of walls, whereby when the walls are in erected position the links are subjected to endwise thrust and the tongues are yieldably supported in inwardly diverging relation to the walls to which they are connected to facilitate their engagement within the recessed ends of the articles packaged.

10 4. A tubular holder for packaging articles having projections at the ends thereof, said holder comprising opposed pairs of hingedly connected walls, one opposed pair of walls having end flaps folded inwardly upon and fixedly secured to the inner sides thereof in approximately parallel relation thereto, the other pair of opposed walls having inwardly directed tongues yieldably connected thereto and struts for said tongues flexibly connected to said flaps, the flexing connections for the struts to the flaps being aligned with the hinging connections for the adjacent walls, whereby when the walls are in erected position, the struts are subjected to end thrust and yieldably support the tongues in inwardly diverging article engaging position.

15 5. A collapsible tubular holder for packaging articles comprising hingedly connected pairs of walls, one opposed pair of walls having inwardly directed article engaging tongues on their end edges, and tongue supporting struts flexibly connected to the inner sides of the other pair of opposed walls with their flexing connections thereto in alignment with the hinging connections for the adjacent walls, said struts being connected to said tongues so that when the walls are collapsed the tongues and said supporting struts collapse on the inner sides of the walls in adjacent side by side relation thereto and when the walls are adjusted on their hinging connections to erected position the tongues are springably supported in an inwardly diverging relation to the walls at a greater distance from the walls than when the walls are in said collapsed position.

20 6. A collapsible tubular article packaging holder comprising hingedly connected walls, one opposed pair of walls having inwardly directed article engaging tongues swingably connected thereto, and tongue supporting struts secured upon the inner sides of the other pair of opposed walls and having a flexing connection therewith aligned with the hinging connection of adjacent walls and having flexing connections to the tongues so that when the walls are positioned in angular relation the struts yieldably support the tongues in an adjacent side by side and inwardly diverging relation to the walls.
